TRANSMITTER, RECEIVER, AND AMPLIFICATION SYSTEM

Heinrich Karl, Jersey City, N. J.

Application December 12, 1939, Serial No. 308,783

12 Claims. (Cl. 179—1)

Part of this invention is also incorporated in the United States Patent No. 2,193,874 that was granted to me under date of March 19, 1940, and the application (Serial No. 116,462) of which was filed December 18, 1936, and said part representing a diaphragm that is an invention distinct from the remainder of said patent application Serial No. 116,462, division was therefore required.

Said diaphragm, being generally made of a core of certain material and a coating thereon that together produce a clearer and more voluminous voice than all steel membranes, is therefore more adapted to suit the public than the latter. Besides the diaphragm there are other co-operating means as for instance a novel way of transforming the sound vibrations into electrical impulses that are thus sent to any remote place that is in electrical connection with said transmitter and thus being adapted to receive said impulses and having them transformed into sound vibrations by the receiver disclosed in the present invention. This invention comprises therefore a transmitter of novel construction and also a receiver of novel construction and both comprising the improved diaphragm mentioned above.

The invention comprises also such handy construction of the transmitter and of the receiver, that both can be detached separately from the standard thereof and simply used as ear and mouth pieces, respectively, whereby only a relatively long cord bearing insulated conductors, keeps the ear and mouth pieces in electrical connection with the remainder of the telephone and thus permits the person using the telephone to hold only the relatively light ear piece in one hand and also, only if desired, the mouth piece, in the other hand.

The invention comprises also means for securing the ear and mouth piece to the standard in connection with which they can be used also.

The invention comprises also a new means for making or interrupting electrical connections with the connecting station and the user on the other end without the necessity of hooking or unhooking the receiver or of placing or taking it off, respectively, from the socket or other part of the telephone.

Furthermore, the invention comprises novel means for placing the ear and mouth piece on a dish-like part for the easy handling at any time of these parts whereby said dish-like part is so constructed that electrical connections will be interrupted when the receiver will be lifted from it.

The sounding of the bell or buzzer will thus be interrupted.

The invention comprises also a system in which a person may use its own, detachable, and therefore, personal ear and mouth piece (receiver and transmitter) and be able to establish telephone connection with the connecting station and consequently with the party with whom said person is then connected.

10 The invention comprises further, new systems of amplifying the electric impulses set up in the connections of the telephone and transforming these impulses into sound vibrations.

The invention comprises diaphragms of the receivers, the latter of which are adapted to amplify the sound which is transformed from said electrical impulses which are then amplified.

15 The invention comprises also a system of amplification in which the voice will be amplified when request therefor is made and such amplification may be had only for one of the two parties or for both.

20 The invention comprises also systems in which telephone amplification will be had, whereby one system will be adaptable for near connections and another for longer distances.

25 The invention comprises also suitable connecting places, other than telephone booths for making connection with the connecting station by means of the detached (personal) ear and mouth piece, and thus becoming connected by telephone with the demanded party.

30 The invention comprises also suitable boxes or covers for the contacts at said connecting places that are or are not confined in telephone booths.

35 Other novel features will appear in the course of the specification.

The invention is illustrated by the accompanying drawings of which:

Figure 1 shows the diaphragm of the receiver in front view;

Figure 2 shows the diaphragm of the receiver in sectional side view;

Figure 3 shows in a sectional view, and enlarged the receiver having the diaphragm of Figures 1 and 2;

Figure 4 is a diagrammatic representation of the connection station (or the central station);

Figure 5 is one of the modes of keeping the ear and mouth piece, that is, the receiver and the transmitter, handy on a dish-like part;

Figure 6 is a sectional representation of the receiver having a cone shaped diaphragm;

Figure 7 shows the diaphragm of the transmitter in front view;

Figure 8 shows in sectional side view the diaphragm of the transmitter shown in Figure 7;

Figure 9 shows in sectional side view a cone shaped diaphragm of the transmitter;

Figure 10 shows in sectional elevation the transmitter which bears primary and secondary transformer windings and having fine springs in connection with the diaphragm for transforming the sound vibrations into electrical impulses; showing also diagrammatically electrical connections and a standard to which the transmitter can be affixed and detached at will; showing also a circuit connector for establishing electric circuit connection with the connecting station;

Figure 11 shows in sectional elevation another type of transmitter whose primary and secondary windings of the transformer are separated from the hull of the transmitter proper although being in electrical connection therewith and the transmitter being of a type that bears a container of gaseous or of liquid or of a semi-liquid matter for transforming the sound vibrations into electrical impulses and having also a circuit connector for the electrical circuit connection with the connecting station, whereby this connector is different from the one shown in Figure 10;

Figure 12 shows another purely mechanical intermediary means for transforming the sound vibrations of the diaphragm into electrical impulses;

Figure 13 shows in section the mechanism of the connector shown also in Figure 11;

Figure 14 shows the special contact cover and coin box;

Figure 15 shows the telephone connections with amplifiers;

Figure 16 shows simplified telephone connections with amplifiers.

Referring to the diaphragm of Figures 1 and 2 there is a frame 1 on which is stretched a sheet of paper 2, of suitable quality and thickness or a piece of silk or of rayon or one of other cloth may serve. A very thin piece of wood, of such character, that like fir, is very adapted to create sound vibrations, is also adaptable. This paper or cloth of silk or rayon or said thin piece of wood is to be properly lacquered or varnished and especially with the kind of lacquer that dries very hard, such as the lacquer used for lacquering violins. If cloth is taken, such as, silk or rayon or others, it might be necessary to make the diaphragm of cone shape in order to stretch the cloth sufficiently. An example of a cone shaped diaphragm of a receiver is shown in Figure 6 which will be described subsequently. If paper is to be used for making the diaphragm it should be made wet with water and mounted on the frame 1 in moist condition. It will then be properly stretched and allowed to dry thoroughly. In the completely dried condition the paper is then sufficiently stretched and can be lacquered. This procedure applies also to the diaphragm shown in Figures 7 and 8.

Referring again to the diaphragm 2 of Figures 1 and 2 there must be iron filings 3 strewn on the still wet lacquer and especially at the part of the paper that will be nearest to the poles of the electromagnet that is then included in the receiver, as can be seen from Figure 3. The iron filings 3 are then only situated around the center of the diaphragm and only on the side that faces the poles of the electromagnet when it deals with a receiver, which is contrary to a known example of a receiver diaphragm which is entirely made of hard rubber or shellac or Celluloid or Choro-

lithion or other materials in which iron in formated or comminuted form may be embedded, which is then contained in all parts of the whole diaphragm. By embedding the iron filings only 5 in the lacquer that coats the side of the core of the paper etc. and especially only the area that faces the poles of the electromagnet, vibration of the diaphragm will be obtained at the slightest electromagnetic impulse in the electromagnet, as will be explained further subsequently, and the vibrations will be the more pronounced when the far greater part of the diaphragm is left free from iron particles that tend to make it heavy. In the latter figure is also shown that the electro-magnet comprises two cores or shanks 4, 5 which are partly enveloped by the windings 6, 7, respectively. The shanks 4, 5 are connected to the shanks 8, 9 of the permanent magnet 10. The end 11, 12 of the shanks 10 4, 5, near the diaphragm, should be about 1, 1½ or 2 of a thousandth of an inch distanced from the diaphragm 2. Connected to the winding 6 is the wire 13 and connected to the winding 7 is the wire 14, and all are in the same circuit. The latter may be grounded at 15, while the wire 13, forming also part of the circuit, is extended to the connecting station, shown in Figure 4, where it forms a contact 16, in which can be inserted the contact 17. This will take place 20 when the operator received a call to connect with the contact 16 which might have a special other number. The operator at the connecting station thus connects the circuit, which when closed, rings the bell 18.

The parts of the receiver that must be kept together, as, the frame 1, the diaphragm 2, the electro-magnet 4, 5, the permanent magnet 10 and the windings 6, 7 are held together by the frame 19 of insulating material which has the special ear piece 20. The conductors 13, 14 are continued in a cord 21, of known make, and are surrounded by insulating material 22.

For protecting the diaphragm 2 a wire screen 23 is placed a little in front of the diaphragm and held in the walls of the ear piece 20. A ring 24 may conceal the end of the narrow hose of the cord 21.

The receiver of Figure 3 may be placed on a dish-like part 25 (see Figure 5) which has its bottom formed as two contacts 26 and 27, of which the one indicated by 26 will be separated from the contact 27 when the receiver will be lifted, as when the person, hearing the sounding of the bell 18, is to listen to the message coming over the telephone and thus places the receiver to the ear. The electric circuit causing the ringing of the bell 18 will be interrupted thereby and the ringing of that bell thus stops. The flat contact 26 will be lifted and thus disconnected from the flat contact 27 by the spring 28.

For announcing that somebody is listening and for making the conversation with the party at the other end of the wire the person that lifted up the receiver first, must then use also the transmitter or mouth piece 29 which may be placed at some other part of the dish-like part 25, as shown in Figure 5. The details of the transmitter will be described subsequently.

Referring to the cone shaped diaphragm 30, shown in Figure 6, it consists preferably of cloth such as silk or rayon although cotton may be used also. The piece of cloth will be stretched on the frame 31, whereby the center point will be held forward by a forward protruding part 32.

that is united with the frame 31. The diaphragm 30 culminates therefore in the point 33 and the cone shaped wall of the diaphragm can be better stretched than with the frame 31 alone. The diaphragm 30, being also the diaphragm of a receiver, must also have the iron filings embedded in the lacquer that covers the surfaces of the cloth or other suitable material.

The cores 34, 35 of the electro-magnet 39 thus must have the ends so inclined, which are nearest to the diaphragm, that they will have the same direction as the cone shaped wall of the diaphragm, in order to be very close to the inner surface of it, but without touching it. 37 indicates the permanent magnet and 38 the part of the frame or hull that will be held against the ear. There might be a cone shaped protection screen 39 employed. The other parts of the receiver of Figure 6 are otherwise like those shown also in Figures 3, 4 and 5.

From the description of the receivers it is shown, that the electric impulses set up in the windings 6, 7 of Figure 3 or the windings 40, 41 of Figure 6, energize the cores 4, 5, 34, 35, respectively. These cores, being thus made magnetic in the degree which is commensurate with the degree of the electric impulses, attract also the iron filings that are embedded in the lacquer of the diaphragms, and since these iron filings cannot separate themselves from the lacquer and consequently from the diaphragms, the latter must therefore make the movements or vibrations which are caused by the alternate attraction and then release of the iron filings that are embedded in the then hardened lacquer. The stiffened diaphragms, being thus forced to vibrate, produce thereby sound waves that conform with the electric impulses set up in the windings and cores of the receiver.

In order to synchronize the vibrations of the diaphragm of the receiver with those of the transmitter it is therefore advantageous to make the diaphragm of the transmitter of the same material that is taken for making the receiver, whereby no iron filings will be embedded in the lacquer. Using for the transmitter the same material of which consist the receiver, is however, not an absolute necessity, since the transmitter diaphragm might consist of one of said other materials mentioned before and even the all-steel membrane might be retained under certain circumstances.

The reason why the materials mentioned, that are non-metallic, are preferable over all metallic diaphragms is, because these materials discounting the frame 1, 31, respectively, and in cooperation with the hardened lacquer being lighter and more sensitive than metallic diaphragms, are adapted to make more pronounced vibrations than the steel membranes and consequently will react upon the slightest impulse, either the sound or the electric impulse. Since then the strong and medium impulses are also proportionally increased there is a greater perceptibility of the sound created by the receiver than it is the case with the all steel diaphragm. This permits again that other parts in the receiver, as well as in the transmitter can be made smaller in size than with the transmitters and receivers, the diaphragms of which are in the form of steel membranes, without impairing thereby the vibrations of the diaphragms.

Referring to the transmitters of which two complete examples are shown, namely, one in Figure 10, which will be described first, and one 75

in Figure 11, one of the purposes of the invention is to make the mouth piece 42 detachable from the standard 43. This permits to hold the relatively small mouthpiece (the transmitter) in one hand and the relatively small receiver (the ear piece) in the other. Many persons like to walk back and forth while talking and do not like to have relatively voluminous or heavy instruments in their hands. The telephoning, while being in bed or in any other situation, is thus made easy and consequently more agreeable. A business man may carry the mouth piece and the ear piece in his pockets while being in the office or in any other place, and may detach them from the contacts 45 that have guide channels 46, 47 into which can be inserted the contact extensions 48, 49 (the insert) that form part of an attachment 50 to which are properly connected the wires 51, 52 in the cord 53. The wires 51, 52 are insulated from each other, as are also the metallic walls of the guide channel 46 from those of the guide channel 47. The contact extensions 48, 49 are also insulated from each other and the former is electrically connected with the wire 51 while the other is connected to the wire 52. To the metallic wall of the guide channel 46 is electrically connected the wire 54 while to the metallic walls of the guide channel 47 is electrically connected the wire 55, which is grounded at 56. Wire 54 is extended to the connecting station that might be the central station. Wire 54 must be in connection with the contact 17.

Another pair of guide channels 57, 58 are provided for to permit the insertion of the contact extensions 59, 60 (the insert) of the receiver (see also Figure 3). The metallic walls of the guide channel 57 are in electrical connection with the wire 54, while the metallic walls of the guide channel 58 are in electrical connection with the wire 55.

If the telephone company would provide guide channels as explained in connection with Figure 10, with every telephone booth and also at many other convenient places, it would facilitate those persons that carry with them their personal receiver and transmitter, to converse by telephone from any of the numerous places by using their own set of transmitter and receiver (the mouth and ear piece). A regular telephone booth might be only miles away.

This innovation is not only made to suit fastidious people that do not like to handle receivers and transmitters that have been handled by numerous other people, but the scheme would enormously simplify the system and reduce enormously the cost of installation of the so simplified apparatus. It would then suit greatly the user of the telephone that may carry his own mouth and ear piece, and would suit greatly the company for the economic and simple way of installation.

Referring more particularly to the scheme shown in Figure 11 the mouth piece (the transmitter) will be detached from the primary and secondary winding 61, 62, respectively, of the transformer 63. The transmitter, thus being reduced in weight, can be made so light and small that it can be carried in the vest pocket. It will then be necessary to install the transformer 63 in some secure place and connect it by the wires 64, 65 to the metallic walls of the guide channels 67. The battery 68 must then be included in this part circuit as well as the primary winding 61. It will be conformable to indicate

by sign or other information, if the guide channels their walls, respectively, are in electrical connection with a transformer. There might be therefore two kinds installed of which one is and the other is not in connection with a transformer.

The circumstance that the diaphragm can be relatively small permits therefore also to make the transmitter comparatively small. The transmitter of Figure 10 may be used at such numerous places by workmen of the telephone company or other agents, in which no transformers are to be installed, while the transmitter of Figure 11 will be used only by private persons, at such places, where the transformers are also in electric connection with the walls of the guide channels.

Other arrangements in the use are obviously possible and also mechanically there are deviations possible, as for instance, the guide channels for the inserts may be arranged at the ends of the wires that are permanently associated with the transmitter (the mouth piece) while then the wires being permanently in electrical connection with the primary winding of the transformer must then be connected to the insert.

In connection with the receiver the insert may also replace the part with the guide channels while the latter will then be part of the detachable portion of the receiver.

In order that the telephone company may be duly recompensed for the use of the telephone connections and the service of connecting, there are in general two ways for receiving its dues. One of these ways consists by including a general fee for a large number of calls when a person acquires a set consisting of a receiver and a transmitter for personal use only. In this case the person that acquires the receiver and transmitter will also be handed a key 68 by means of which the cover 69 can be unlocked and turned in such position that it permits the insertion of the insert. A similar cover should also be in connection with the transmitter guide channels. The cover 69, however, should be big enough to cover all four guide channels, namely, those indicated by 46, 47 and 57, 58.

Since the scheme in connection with the transmitter of Figure 11 is similar to that shown in Figure 10 the same applies also to the guide channels that will be used for connecting the transmitter of Figure 11 and a cover will serve for protecting the otherwise exposed contacts, whereby the person, having the key, can thus open the cover and insert the inserts of his mouth piece (the transmitter) and ear piece (the receiver). The other mode of getting its dues is, that the telephone company provides a nickel drop near every lock of the cover 69 and to construct the lock so, that part of it prepares the lock bolt for being pushed to open position which is then effected by the key which the caller carries with him and which should be suitably attached to the transmitter or to the receiver.

A convenient structure of such lock is illustrated in Figure 14. The cover 69 is shown partly broken away to show the other mechanisms that co-operate with the lock. The lock bolt 70 is thus shown in locking position, whereby a spring sustained relatively thin bar 71 will be moved between the wall 72 and the end wall 73 of the bolt 70. The latter thus cannot move backward, even if the key is inserted and it is tried to turn it. Only after the insertion of a coin, say a nickel, the thin bar 71, that might

be pivoted, will be pushed down and out of the way of the lock bolt 70. The additional weight of the nickel forces the relatively weak spring 75 down, bringing thus also the thin bar 71 down and in engagement with two spring contacts 76, 77 that usually are separated from each other. These contacts 76, 77 form part of an electric circuit by means of which, and in co-operation with a sounding or visually perceptible means, 10 will be announced that a nickel has been dropped in that certain box. The operator in the connecting station may thus make a note etc. and then disconnect temporarily the bell or whatever means are employed for announcing the insertion of the nickel and will then listen to the caller and make connection with the demanded number. At this instant the caller might ask for amplification if he should be hard of hearing or if he simply likes it better, or if several persons are eager to listen at the same time. The details in connection with the amplification will be pointed out subsequently.

The spring contacts 76, 77 are so formed that they hold the thin bar 71 and thus allow the nickel 78 to drop through another slit to fall into a special box, especially provided for the coins. This special box is shown underneath and since similar boxes are well known, is not further described; the same will be also provided 20 with adequate locking means as known. The lock bolt 70 is always urged by the spring 79 to the forward position in which it locks the cover 69 when the latter is pressed against the casing 80. While thus locking the cover 69, a 25 part 81 in the box will separate the two spring contacts and the thin bar 71, being urged upward will then be situated between the wall 72 and the rear edge 73 of the lock bolt 70 and will thus prevent the latter to be moved by a key, or 30 moved otherwise, to open position unless the required coin is inserted. It will be noted, that through the forward urging of the lock bolt 70, by the spring 79, no pressure will be exerted upon the thin bar 71 excepting a temporary pressure 35 when somebody tries to move the lock bolt 70 to open position with a key without, however, inserting the coin. The thin bar having no obstruction, other than that of the spring 75, readily moves down, following the weight of the 40 nickel.

Referring to the other details of the transmitters the diaphragm, which might also be cone-shaped, as shown in Figure 9, does not need to have iron filings embedded in the lacquer that 45 covers the cloth, or paper, or thin wood piece, but for creating a diaphragm that has the same weight and consequently the same vibrating quality as has the diaphragm 2 or 30 of the receiver, there may be iron filings strewn in the 50 still wet lacquer that covers the cloth, paper or wood, or other suitable fibrous material, of the diaphragm. The synchronization will thus be had that renders the electric impulses into sound waves that correspond with those caused by the 55 person that speaks into the transmitter.

The transmitter of Figure 9 that has a cone shaped diaphragm 82 is similarly constructed as the diaphragm of Figure 6. In addition, however, there are lacquered fibres or bristles or horse hair, that is lacquered, or other delicate means 60 83 of certain stiffness and flexibility, that are secured to the part of the diaphragm that vibrates the most vigorously, which is the part 65 between the apex 33 and the frame 31, and which means are adapted to translate the vibra- 70 75

tions of the diaphragm 82 upon the metallic membrane 84, which does not need to be of steel, but of any other suitable metal, as for instance silver, copper or brass. The ends of these fibres etc. 83, that touch the metallic membrane, should advantageously be provided with an insulating material, so as to prevent electric energy to deteriorate or burn the fibres etc. and also the diaphragm, because the metallic membrane forms a connection of an electric circuit. Behind the metallic membrane 84 there is metal wool 85 placed which should touch the metallic membrane and also the conducting plate or part 86. Instead of the metal wool there might be granules of carbon or graphite or charcoal employed although the metal wool, preferably of a good conductor, is preferable on account of its better conductivity and flexibility. To the metallic membrane 84 is connected the wire 87 which leads to one of the ends of the primary winding of the transformer, which is not shown, but since the mouth piece shown in Figure 9 is supposed to be of the character of the mouth piece shown in Figure 11, which is detachable from the part that embraces the transformer, reference is therefore had to that particular arrangement, shown in Figure 11, which has been described previously. Referring again to Figure 9 the wire 88 that is connected to the plate 86 leads to the battery which in Figure 11 is indicated by 89. The wire indicated by 64 in Figure 11 leads then to the other end of the primary winding to which it is connected.

Referring to the Figure 10 the diaphragm 90, shown also in Figures 7 and 8, is flatly mounted on the frame 91, and the latter is insertable in the hull 42. The diaphragm 90 may have also the iron filings 3' as it is with the diaphragm of the receiver, but only for synchronizing purposes, as has been explained previously.

At the interior side of the diaphragm 90, and centrally located, there is a part 92 secured that must be very light and which could consist of the marrow of some plants or of cork and the free end should be covered with insulating material. A very fine leaf spring 93 is secured with its one end at 94, where it is insulated from other parts, but a conductor 95 is electrically connected thereto. The free end part slightly touches the insulating material on the part 92 and the free end part of another fine leaf spring 96 touches also slightly the leaf spring 93. Leaf spring 96 is secured with its other end to the plate or wall 97 which is in electrical connection with the primary winding 98. The latter has also at its other end a conductor 99 which leads to the right side of the battery 100. To the left side of that battery is connected the wire 95. To the secondary winding 101 is connected the wire 52, while the wire 51 is not directly connected to the other end of that winding. There is a push button 102 of any convenient character with which an electrical connection and disconnection between said other end of the secondary winding 101 and the wire 51 can be made. This switching device 102 might chiefly serve when the insert of the transmitter is inserted in the guide channels at home, but no conversation is intended. The push button thus will remain in circuit disconnecting position. Even with connecting contacts 45 (guide channels) at other places than the home, the push button will be handy for interrupting communication until the right moment is at hand. In order to restore the push button 102 to non-contacting position, in which it interrupts the

electrical connection between the wire 51 and the secondary winding 101, after it had been pushed in to contacting position, there is another push button 103 arranged at the opposite side of the hull and a partly curved rod 104 is secured to it and also to the push button 102. If then the push button 102 will be pushed in, the push button 103 will then be pushed out, and the push button 102 is then in contacting position. By pushing then the push button 103 in again the push button 102 will thus be pushed out by the rod 104 and will make said disconnection between the wire 51 and the secondary winding 101.

Looking now at Figure 4 it will be seen that the bulb 105 will light up when the circuit will be closed that comprises the battery 100, because the wire 54 also shown in Figure 10 is in electrical connection with the secondary winding 101 whose other end is grounded at 56. The operator at the connecting station may then connect after any known kind of announcement including the voice of the caller, the contact (switch plug) 17 with the contact 16 and thus establish an electric connection with the bell 18 and with the receiver of Figure 3 or Figure 5 or both.

In Figure 11 the main purpose of the construction consists in reducing still more the weight of the transmitter, so that the latter may be carried easily in the pocket of any person or in the hand bag of a lady, including also the receiver of Figure 3 which is also the one shown in Figure 5, or it may be the receiver shown in Figure 6.

The transmitter of Figure 11 distinguishes itself greatly from the transmitter of Figure 10. The diaphragm 107 is similar to the diaphragm 90 and is also similarly mounted on the frame 108. At the center of the interior side of the diaphragm 107 there is a light part 109 secured, in which is inserted a very fine but stiff wire or bristle 110. The right side end of the wire or bristle 110 abuts against a steel membrane 111 or one of any other suitable metal, such as silver, copper etc. This membrane closes up a vessel 112 of glass or porcelain or of any other suitable insulating material that should have an opening 113, that can be tightly closed by a stopper or the like means 114. At the center of the right side wall of the vessel 112 penetrates a conductor 115 that is secured to a plate 116, which may be of copper or of any other suitable metal. The conductor 115 is extended into the cord 117 and is insulated therefrom. Likewise 115 is also a conductor 118 extended into the cord 117 and insulated from both the latter and the conductor 115. Conductor 118 is secured to the metal membrane 111 at a part that is nearest to the outer edge thereof, and the other end of that conductor forms the insert extension 119 that is insulated from the insert extension 120. The latter is the end formation of the conductor 115. Into the vessel 112 will be introduced the gas or vapor that is known to be a good electricity conductor and which is also adapted to correctly transform the vibrations of the membrane into electrical impulses when an electric current is passed through it. It is therefore important that said gas or vapor has the correct density and that only then the closing means 114 should close up the vessel 112.

Any gas that does not explode or expand too heavily will be suitable, and in such category may be ranged lighting gas although others may be even better. Among the vapors, that could

be used, must be ranged first the fumes of mercury.

Instead of fumes or gas there might be liquids or semi-liquids filled in the vessel 112, which again might contain suitable ingredients. One of these semi-liquid means might consist of paste in soft condition or any suitable kind of jelly having carbon or charcoal dust or powdered graphite, iron, silver or copper or brass mixed therein in certain proportion.

If the insert extensions 119, 120 are inserted into the guide channels of the stationary connecting part 67 the electric circuit will be closed that comprises the following conductors: the battery 68, the wire 64, the primary winding 61 of the transformer 63, the wire 65, the walls of the guide channel in which is inserted the insert 120, the wire 115, the plate 116, the gas or fumes or liquid or jelly etc. in the vessel 112, the membrane 111, the wire 118, the insert extension 119, the walls of the guide channel in which the extension 119 is inserted, the wire 121 that is connected at the left side of battery 68.

The person speaking against the diaphragm 107 brings the same thereby into vibration and these vibrations are transmitted to the metallic membrane 111 by means of the wire or bristle 110. The gas or fumes or other mentioned matter contained in the vessel 112 takes up the vibrations made by the metallic membrane 111 and since electric current flows at the same time through the metallic membrane 111 and through the fumes or gas or liquids etc., the vibrations will thus be rendered into electric impulses, which the plate 116 takes up and imparts to the primary winding 61 through the wires 115, 118, the insert extensions 119, 120 and the contacts in the connecting part 67, the battery 68 and the wires 64, 65. The secondary winding 62 still more clarifies the impulses and if the connector 123 is in closed position, conversation can then be had with the connecting station and when the operator connects with the number that is demanded, conversation will then be had with the party whose telephone is thus connected.

The secondary winding 62 is in electrical connection with the connecting station shown in Figure 4 or Figure 15 or Figure 16 and has similar connections as has been explained in connection with the Figure 10.

In order to make the mouth piece of Figure 11 as light as possible so that it can be carried in the pocket of its owner, the connector is not incorporated with the mouth piece, but is brought in connection with the conductor 122 and is indicated by 123. For connecting the mouth and ear piece at such places that are remote from the home or office the connector will not be needed, since electric connection will be established with the connecting station at the moment the inserts are inserted in the guide channels.

The connector 123 which is shown in section in Figure 13 has a push button 124 that is movably arranged in the body 125 of insulating material, and that push button bears the contact part 126. The latter is so formed at its ends that they (the latter) snap upon the ends of the wires 127, 128 when the push button 124 is pushed in. Electrical connection is thus created between these two wires. The push button 129 has a part 130 that is also connected to the push button 124. If then the push button 129 is pushed inwards the push button 124 will be pushed outwards and disconnects its contact part 126 from the wires 127, 128.

Having described the details of some preferable types of the receivers and transmitters it is to mention that the non-metallic diaphragms are greatly advantageous for the transmission and reception of the amplified voice. This permits again the installation of amplifiers of the radio type at the connecting stations (see Figures 4, 15 and 16) where the electric impulses coming over the wire will then be amplified upon request. Various forms are thus adaptable. In one form shown in Figure 4, the operator at the connecting station disconnects the contact 17 from the contact 16, but closes the switches 132 and 133. Through this action the wire 54 or 122' will be brought into electrical connection with the amplifier B and the wire 13 will be electrically connected to the amplifier C. If the caller at the transmitter that is connected to the wire 54 or 122' requests that the operator connects the amplifier and tunes it up to the desired volume, the electric impulses set up in the wire 13 and the secondary winding of the transformer, that is in electrical connection with the wire 13, thus will be amplified in the amplifier C, and in such state the electric impulses will be impressed upon the wire 54 or 122' and consequently the electromagnet 4, 5 or 34, 35 of the receiver vibrates the diaphragm in such degree that the voice produced thereby is in intensity above the voice that is derived from electrical impulses that did not receive amplification. On the other hand the wire 54 or 122' that is in electrical connection with the amplifier B might also have the electrical impulses amplified if it will be so requested from the party at the receiving end of the wire. If no such request will be made, then the amplifier B will be tuned only to such degree in which the electrical impulses originated by the transmitter in connection with the wire 54 or 122' and the respective secondary winding thereof of the transformer will be transferred without amplification upon the wire 13 and the electromagnets 4, 5 or 34, 35 in about the same degree as they are produced in the wires 54 or 122'. The circumstance, that the party listening at the receiver at the end of wire 13 will hear its own voice amplified, makes it then necessary to cover the front side of the ear piece, in any suitable way, while transmitting, that is, speaking into the transmitter; or the ear piece may be simply held away from the ear.

This inconvenience, which is caused by the amplification of the electric impulses set up in the wires 54 or 122 and transferred through the amplifier B to wire 13 and the receiver at the other end, can be remedied when a special wire 134 (see Figure 15) will be connected to the secondary winding of the transformer of the transmitter T, whereby the wire 54' will be connected to the receiver R only.

By separating the amplifier D completely from the wire 54' and connecting the wire 134 to the amplifier D by means of the switch 132' amplification will be had in the receiver R, over the wire 13'. If the party at the receiver R wishes to have also amplification of the words coming over the wire, the operator, when thus informed, disconnects then the contact 17 from the contact 16 and closes the switch 133'. The words spoken into the transmitter T' will be amplified by the amplifier E and in such amplification will be had at the receiver R. In order that the own words will not be heard in the receivers by the person speaking into the transmitter T or T', the switches 134', 135' should be opened.

A simplification of the system, shown in Figure 16, is that only one wire leads from the receiver R2 and the transmitter T2 to the connecting station F and also only the wire 13" from the receiver R3 and the transmitter T3 to said connecting station F. In order to avoid that the own words will be heard at the receiver by a person speaking into the transmitter not to say the amplified voice, there is a system of very sensitive relays employed that act at the slightest electrical impulse that energizes the cores of said relays. For simply connecting the telephones of two parties that wish to have conversation with each other the contact 17 (the insert or switch plug) is to be inserted into the contact 16. The party using the receiver R2 and the transmitter T2, wishing to have the words amplified that come from the connected phone with the receiver R3 and transmitter T3, order so from the operator at the connecting station F. The operator pulls then the switch plug 17 out of the contact 16 and closes the switch 137. Electric connection is thus established between the receiver R3 and transmitter T3, on the one hand and the amplifier G, on the other. It must be remembered that the armature 143 normally is in its dropped position in which it contacts with the contact 144. The amplified electric impulses are impressed upon the winding of the relay 139 by the wire 138. This relay attracts thereby its armature 140 and the latter becomes thus disengaged from the contact 141 of the lead 142 that leads to the amplifier H. The amplified electric impulses thus cannot flow to the amplifier H and are forced to concentrate on the receiver R2 and the secondary winding of the transformer 145 that is grounded at 146. The electromagnet 4, 5 (or 34, 35) in the receiver R2 vibrates the diaphragm 3, (30), commensurate with the degree of the electric impulses, which it receives, and since they are then amplified, the voice, created by the vibrations of the diaphragm, is then also commensurately amplified.

The armature 140, being thereby disconnected from the contact 141, no sound, that was spoken into the transmitter T3, will be heard amplified at the receiver R3.

The party at the telephone with the receiver R2 and transmitter T2 must also be able to communicate (speak) with the party at the phone with the receiver R3 and transmitter T3; therefore, as soon as the armature 140 drops electric connection is established with said party at the right, namely the phone with the receiver R3 and the transmitter T3. The electric connections, include the wire 142, the amplifier H, which, however, is tuned only to the degree which will produce a sound at the receiver R3 that equals that which is obtained when no amplification will be had, that is, when the contact 17 is simply connected to the contact 16. The relatively weak electrical impulse is adapted to energize sufficiently the core of the relay 149 so that the armatures 143 and 150 will be attracted and an electric connection with the receiver R3 and the secondary winding 62 of the transformer 63 is established, whereby said secondary winding is grounded at 155.

If the party at the telephone of the receiver R3 and transmitter T3 wishes to get also amplification and notifies the operator at the connecting station F, the operator simply tunes up the amplifier H to the desired volume. The amplification will be impressed upon the lead 148, the winding of the relay 149 and since the armatures 75

143 and 150 are attracted thereby connection with the amplifier G and conductors associated therewith will be severed, but electric connection with the receiver R3 and the secondary winding 62 and ground 155 (transmitter T3) established. The party at the phone of the latter receiver and transmitter will thus have amplification in the desired degree without having its own words amplified at the receiver R3 that are spoken into the transmitter T3.

A still greater simplification consists, in using only one amplifier, as for instance the one indicated by G. In this event the switch plug (contact) 17 is to be contacted with the wire 152 or directly with the proper contact of the amplifier G. A wire is then to be connected to the wire 138 and to the winding of the relay 149. Amplification, however, will be had at the receiver simultaneously with the own words spoken in the transmitter.

The system illustrated in Figure 15 might be advantageous with connections in which relatively little wire will be needed as, for instance, when it deals with an installation that is limited to the home, an estate or to a factory or to some not too far distanced or neighboring buildings only. The system contemplated in Figure 16, however, is more adapted for longer distances and long distance calls, since only one wire is needed to connect the receiver and transmitter with the connecting station, the central station, respectively. There is at least one great advantage in connection with the amplifiers that are situated at the connecting station only, because the necessary care and correct handling and better protection of the same is thus assured and not many amplifiers might be needed.

Referring to the transmitter of Figure 11 there is also a standard 137 contemplated that is indicated by dotted lines. Since the structure and shape of the mouth piece differs from that of Figure 10 a method is therefore adaptable in which by means of hooks 138, 139 the mouth piece will be held in vertical position, which is the position in which the diaphragm is also vertical. A spring 140 will urge the hook 139 against the hull 29 and the springy part 141 will pull the hook 138 and consequently the upper part of the hull 29 against the standard 137, permitting at the same time the separation of the hook 138 from the hull 29 and the latter from the hook 139 and then of the standard 137. The latter may also have all the improvements which are, for instance, known with standards of microphones.

Referring to Figure 12 the scheme employed might find as well use with the disclosure of Figure 9 or even with that of Figure 10. It consists of placing carbon granules 143' or graphite or charcoal or a mixture of these ingredients in the space, situated between the metal membrane 144' and the metallic wall 145', which is in electrical connection with the primary winding of the transformer, shown only in Figures 10 and 11. The membrane 144' will be vibrated by the diaphragm 146', its attached part 147', respectively, whereupon the granules 143' transform the vibrations into electrical impulses. In connection with some of the receivers, especially those that have cone shaped diaphragms, as, for instance, shown in Figure 6, the pole ends of the cores of the electro-magnet may consist of two or more branches when it deals with cores that must be close to parts of the diaphragm that vibrate the most violently. One branch

end may thus face the part of the diaphragm that is half way between the outer frame and the center point, the apex of the diaphragm, and the other somewhat nearer to the apex, as also shown in Figure 6. The former may, however, suffice in this case.

Summarizing the invention, first, the diaphragms of the receivers as well as of the transmitters are contemplated to be of other materials, chiefly fibrous materials, than of all metal, because the atomic structure of metals is not so favorable for giving the membranes, made of metal, the relatively wide range of vibration which is, however, inherent with the materials contemplated in the present invention. The means for coating the diaphragms, of which lacquer, or a certain kind of varnish is contemplated, protect the diaphragm as it gives also the vibrating quality to it when in dry condition.

Therefore, through the addition of iron filings in the lacquer that covers said non-metallic material of the core of the diaphragm of the receiver and especially the side of the core and only the area that faces the poles of the electromagnet, the electromagnetic impulses will be transformed into sound vibrations.

Further, a system is created in which thanks to the non-metallic diaphragm, being adapted to increase the sound vibrations and thus increase the volume of the voice caused by the electrical impulses sent over the wire, the decrease of the size and weight of the ear and mouth piece is thus permitted.

Furthermore, the forming of the ear and mouth pieces as detachable parts that can be used as the personal ear and mouth piece and which are adapted to be carried in the pocket or in a hand bag, when not in use, is one of the results.

Furthermore, the ear and mouth piece (the receiver and transmitter), through their wider range of vibrating movement, permit the amplification of the electric impulses set up and the commensurate amplification of the sound with the receiver, the ear piece.

Furthermore, since amplification should be made only when so ordered, the system comprises therefore such connections and apparatus that permit amplification only for the party, asking for it, whereby amplification will be had in the desired volume for all, that is the two parties speaking together over the telephone, if so ordered and the connections are made.

Furthermore, thanks to the proper arrangements of the electric connections and certain other means of one simplified embodiment, the words spoken into the transmitter by a person will not be heard in amplified volume in the receiver to which listens that person.

Furthermore, the system comprises also such other electric connections in which the words will not be heard at the receiver at which the person listens that speaks them into the transmitter.

Furthermore, such simplified electric connections are also devised which, however, amplify the words spoken into the receiver if such amplification is demanded, whereby the words spoken into both transmitters will be heard in amplified volume at both receivers.

Furthermore, the fact that the transmitter and receiver can be detached and carried on the person that possesses them, permits the installation of contacts with electric connections leading to the connecting station, whereby these con-

tacts do not need to be confined solely in telephone booths, in which, however, they may be arranged also.

Furthermore, the creation of new means for the transformation of the sound vibrations into electrical impulses favor the clear and voluminous transmission of the voice and favor also the amplification thereof.

Furthermore, the addition to the diaphragm of the transmitter of iron filings for synchronization with the diaphragms of the receivers.

Furthermore, the creation of the cone shaped diaphragm and of the flat diaphragm.

Furthermore, the creation of a handy dish-like part on which the light and handy ear and mouth pieces can be placed so as to be ready for the use at any time.

Furthermore, the use of liquid and semi-liquid or jelly like means for the transformation of the sound vibrations into electrical impulses.

Furthermore, the use of metal wool for the transformation of the sound vibrations into electrical impulses.

Furthermore, the arrangement of fine springs for the transformation of the sound vibrations into electrical impulses.

Furthermore, the transmission of the vibrations of the non-metallic diaphragm upon a metallic membrane.

Furthermore, the disconnection of the battery, the primary and the secondary windings of the transformer from the transmitter, thus permitting the latter to be very light and adapted to be carried on the person when not in use, and consequently the confining of said battery and transformer at the places with the stationary contacts or at the connecting station whereby only few batteries and transformers will be needed for a large number of stationary contacts, that offer the contacting of said transmitter as well as the receiver and therethrough the electric connection with the connecting station.

Furthermore, electro-magnets having cores, the pole ends thereof may be branched.

What is claimed is:

1. A telephone transmitter and a receiver, the latter associated with an electro-magnet, both, the transmitter and receiver, having a diaphragm of non-metallic material, the diaphragm consisting of a core held by stretching means in such position that it assumes the shape of a cone, and both cores of the diaphragms lacquered and at least the diaphragm of the receiver having iron filings embedded in the lacquer at the parts of the diaphragm only that are distant from said stretching means and facing the poles of said electro-magnet.

2. A telephone transmitter having a non-metallic diaphragm, a part secured to the latter and touching a metallic electrical conducting part of flexible property, and other metallic means of flexible property touching said metallic electrical conducting part, and both said metallic electrical conducting part and said other metallic means adapted to vibrate in unison with said diaphragm, and said metallic means in connection with an electric circuit, transforming the vibrations into electrical impulses.

3. A telephone transmitter, a diaphragm of non-metallic material, comprised in said transmitter, the diaphragm lacquered and iron particles embedded in said lacquer, a membrane of metal, a stiff and light part secured to said diaphragm and having an end, the latter normally touching slightly the membrane of metal and

adapted to transfer the vibrations of said diaphragm upon said membrane of metal, the latter connected in an electric circuit, a vessel of insulating material, said membrane covering said vessel the latter containing a wet substance that is adapted to take up the vibrations of said membrane of metal and change them into electrical impulses and impress the latter upon other electrical conductors including a transformer.

4. A telephone transmitter, a diaphragm of non-metallic material comprised in said transmitter, the diaphragm lacquered, a membrane of metal, a light means secured to said diaphragm and touching lightly said membrane of metal and adapted to transfer the vibrations of said non-metallic diaphragm upon said membrane of metal, the latter connected in an electric circuit, a vessel of insulating material, said membrane covering part of said vessel, the latter containing gaseous matter that is adapted to take up the vibrations of said membrane of metal and impress them upon other electrical conductors, including a plate and a transformer, in form of electrical impulses.

5. A telephone receiver and transmitter, adapted to be carried in the pocket or handbag of a person, adapted also to be connected and disconnected from contacts that are in connection with the stationary circuit connections of the connecting station, a dish-like part permitting the placing upon it said receiver and transmitter, a standard adapted to hold said transmitter and a standard to hold said receiver in the vertical positions.

6. A telephone receiver and transmitter, a dish-like part adapted to receive said receiver and transmitter for the handy handling thereof, said dish-like part having a part consisting of electrical contacts and the latter included in an electrical circuit that includes also a means for announcing a call, one of said electrical contacts adapted to disconnect itself from the other when said receiver is taken from said dish-like part, thus opening the circuit in which said means for announcing is included, and thus stop the same in its function.

7. A telephone receiver and transmitter, stationary circuit connections of a telephone system, including electrical connecting parts at various locations and some including a cord with electrical conductors, the transmitter having electrical connecting parts and adapted to be electrically connected to said electrical connecting parts that include the conductors in said cord, a push button adapted to stay in the pushed-in position and thus make an electrical connection that closes the circuit in which said transmitter is included, and another push button for pushing the first mentioned push button out and in circuit disconnecting position.

8. Stationary circuit connections and a connecting station of a telephone system including electrical connecting parts at various points, a telephone receiver and transmitter having connecting means for the electrical connection with said electrical connecting parts and adapted to be electrically connected to said electrical connecting parts every time a telephone call is to be made and likewise to be detached from said electrical connecting parts every time the telephone call is finished and adapted to be carried in a pocket or in a hand bag, the transmitter comprising circuit closing and opening switch means, said switch means adapted to let the call-

er make electrical connection with said connecting station at any time after said connecting means have been connected to said stationary circuit connections.

5 9. A telephone system comprising a connecting station and electric conductors leading to various points, stationary contact means at said points being in electrical connection with said connecting station through said conductors, receivers and transmitters adapted to be carried by a person in its pocket or in a hand bag, and thus made possible through the general reduction in size of these receivers and transmitters and on account of the elimination of the transmitter and the battery and the transfer of these parts to a suitable stationary place, said receivers and transmitters having contacts in connection with conductors in a cord and these contacts adapted to be contacted with said stationary contact means and to be held together in such condition unless separated therefrom, means for covering said stationary contact means for protecting the same and means preventing the undue opening of them including means not permitting the opening of covering means unless a coin of a predetermined value is inserted.

10 10. A telephone system comprising a connecting station with an operator and electric conductors leading to various points including also the telephone booths, stationary contacts at said points, personal receivers and transmitters including contacts, adapted to be carried by the person possessing them and said last mentioned contacts adapted to be connected with said stationary contacts and thus creating electrical connection with said connecting station, said personal receivers and transmitters comprising a non-metallic diaphragm and at least the diaphragm of the receiver having iron filings embedded therein and being in proximity of cores of an electro-magnetical device, and reacting upon the energization of said cores by vibrating said diaphragm in the degree that is commensurate with the degree of the electric impulses set up in said cores, and thus being adapted to amplify also the sound, an amplifier at said connecting station adapted to increase said electric impulses and connections for connecting the amplifier with said personal receiver and also with the transmitter of the phone of another party then connected by the operator at said connecting station, and means for providing amplification also for said, last mentioned, other party, if such amplification should be requested, the receivers and transmitters of the phone of said last mentioned party having non-metallic diaphragms and at least the diaphragm thereof of the receiver having iron filings embedded therein and the diaphragm of the receiver adapted also to amplify the sound commensurate with the electric impulses set up in the electro-magnet of that receiver, and said electric impulses may be amplified by an amplifier at said connecting station.

11. A telephone system comprising a connecting station and electric conductors leading therefrom to various points including also telephone booths, receivers and transmitters at said points and electric contacts for the insertion of contacts of personal detachable receivers and transmitters, the receivers comprising electro-magnets and diaphragms, the latter adapted to transform the magnetic impulses set up in said electro-magnets into sound, increasing and decreasing it in intensity commensurate with the in-

crease and decrease of the electric impulses set up in the conductors that are in electrical connection with said electro-magnets, an amplifier at said connecting station, electrical conductors leading from every transmitter to said connecting station and means for connecting them to said amplifier, separate electrical conductors leading from said receivers to said connecting station and means for connecting them to said amplifier, in such way, as to receive the output of the amplified electric impulses set up in the electrical conductors of said transmitters, means for electrically connecting the electrical conductors of one of said receivers and of one of said conductors that will be at hand at any of said points and thus permit the connection by means of known contacts of two telephones of parties that want to have conversation together without said electrical conductors being then in electrical connection with said amplifier and consequently without amplification of the sound produced by the transmitter.

12. A telephone system comprising a connecting station and electric conductors leading therefrom to various points including also telephone booths, receivers and transmitters at said points and electric contacts for the insertion of con-

tacts of detachable receivers and transmitters, the receivers comprising electro-magnets and diaphragms, the latter adapted to transform the magnetic impulses, set up in said electro-magnets, into sound, commensurate with the intensity of said magnetic impulses, an amplifier at said connecting station and connecting means for simply electrically connecting two of said electrical conductors, connecting means for connecting one of said electrical conductors with said amplifier and a relay the winding of which is in electrical connection with the electrical conductors that receive the output of said amplifier, a contact of said relay and an armature thereof normally contacting with said contact, another amplifier, said contact electrically connected with said other amplifier another relay, the winding of the latter electrically connected with said other amplifier and adapted to interrupt at times one of said electrical conductors and at the same time to establish electrical connection with said other amplifier and with the receiver and transmitter in connection with said last mentioned electrical conductor, so that the output of said other amplifier reaches the last mentioned receiver.

HEINRICH KARL.
